UNITED STATES PATENT OFFICE

ARTHUR C. DAMAN AND LELAND H. LOGUE, OF DENVER, COLORADO, ASSIGNEES TO
DENVER EQUIPMENT CO., OF DENVER, COLORADO, A CORPORATION OF COLORADO

ROCK CRUSHER

Application filed April 21, 1928. Serial No. 271,811.

This invention relates to a rock crusher of the reciprocating jaw type and has for its principal object the provision of a crusher which will have a greater capacity for a given size and power than present crushers.

Jaw crushers as at present constructed are so arranged that the cross sectional area between the jaws decreases as the discharge is approached so that choking and over crushing results. The capacity of a crusher is, of course, limited by the smallest cross sectional area in the flow channel between the jaws. To develop maximum capacity, there should be no restriction of the area in the flow channel so that the crushed material can be immediately voided to allow the material being crushed to travel as rapidly as its reduction in size will permit.

Another object of this invention is to so construct the crusher jaws that the cross sectional area of the rock passage will be practically uniform from the feed to the discharge extremities.

Still another object of the invention is to impart a lateral grinding action to the jaws in combination with the closing or crushing action.

A further object is to cause one side of the movable jaw of the crusher to move away from the fixed jaw in advance of the other side so that the crushed material will spread and flow toward the sides of the jaw rather than flow straight through the middle portion, thus presenting a maximum surface to the action of the jaws.

A still further object is to provide a crusher with a movable jaw which will have a combination of motions in all lateral directions so that a chewing action as well as a crushing action is obtained.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of

the drawings and throughout the description.

In the drawings:—

Fig. 1 is an end elevation of the improved crusher looking toward the fixed jaw. 55

Fig. 2 is a vertical cross section taken on the line 2—2, Fig. 4.

Fig. 3 is a longitudinal vertical cross section taken on the line 3—3, Fig. 1.

Fig. 4 is a plan view of the crusher. 60

The invention comprises a base frame 10, carrying two inwardly curved side frames 11, which support an operating shaft 12. The shaft 12, carries the usual fly wheels 13, and belt pulley 14, and is provided with two adjacent eccentrics 15 and 16, operatively connected to swing a movable jaw 18, and a fixed jaw 19.

The fixed jaw 19, is carried on an eccentric 20, on an adjusting shaft 21, which can be rotated through the medium of a worm 22, and worm gear 23, to cause the fixed jaw to approach the movable jaw so as to regulate the size of the finished product. The upper portion of the fixed jaw 19 slides on a supporting shaft 24, having a squared portion 25, which rides in an elongated rectangular bearing opening 26.

The movable jaw 18 is carried on a supporting shaft 27, having a squared portion 28, which passes through a relatively wide bearing opening 29 in the jaw. The jaw 18 is secured to the supporting shaft 27, by means of a pivot pin 30. By this construction a universal joint is provided so that the movable 35 jaw can swing in a horizontal arc about the pin 30 and in a vertical arc by rotating the shaft 27 in the side frames 11.

The movable jaw is reciprocated by means of pitmen 31 and 32, which ride on the eccentrics 15 and 16, respectively. The rotation of the shaft 12, imparts a vertical reciprocation to the pitmen 31 and 32. The eccentrics 15 and 16 are placed slightly out of alignment with each other so that the pitmen will be out of step with each other in their movements. The pitmen operate the movable jaw through the medium of toggle members acting between a cross brace 34, and the movable 100

jaw 18. The cross brace 34 is rigidly fixed between the side frames 11.

The toggle members comprise a pair of toggle plates 35 and 37 and a pair of toggle bars 36 and 38. The pitman 32 acts between the rear toggle plate 35 and the front toggle bar 36. The pitman 33 operates between the rear toggle plate 37 and the front toggle bar 38. The toggle plates 35 and 37 are relatively wide and are arranged with cylindrical bearings at their extremities which ride in depressions in the cross bar 34 and in the pitmen 32 and 33. The toggle bars 36 and 37 are provided with cylindrical bearing extremities as illustrated which ride in semi-cylindrical depressions in the movable jaw 18 and in the pitmen 32 and 33.

The entire toggle joint construction is maintained in position by means of compression springs 39 which act upon draw bars 40, to pull the movable jaw toward the cross bar 34, thus firmly clamping the toggle joint members in position. The heads of the draw bars 40 are held in yokes 44 on the movable jaw 18.

The crushing face of the movable jaw extends from a flat surface at its upper portion to a convex bulge 41 at its lower portion which accommodates the rocking or chewing action. The crushing face of the fixed jaw 19 extends from a flat plane surface at its upper portion to a concaved depression 42, to receive the bulge 41, at its lower portion. The lower extremity of the movable jaw is curved forwardly so as to extend partially under the fixed jaw 19, as illustrated in Fig. 3. This acts to retard the material and increase the crushing surface.

Assuming the shaft 12 to be rotating in an anti-clock-wise direction, in Fig. 3, as indicated by the arrow, the operation of the jaw will be as follows: The eccentric 15 will start the pitman 32 downwardly causing the toggle plate 35 and toggle bar 36 to force the far side of the movable jaw 18 forwardly. The eccentric 16 will then start the pitman 33 downwardly causing the toggle plate 37 and the toggle bar 38 to move the near side of the movable plate forwardly. The far side 60 of the movable jaw will reverse and begin its rearward movement before the near side reaches the extent of its forward movement, thus resulting in a rotative action on the movable jaw as well as a forward movement thereof. This compounded action serves to roll the rock while it is being crushed and causes the movable jaw to rock in a horizontal plane about the pin 30. It also causes the crushed rock to spread over the crushing surfaces.

The lower sides of both the fixed jaw 19 and the movable jaw 18 are wider than the upper parts thereof, so as to create a crushing cavity which extends from a practically square opening at the top to a long narrow

curved opening at the bottom. As the rocks become smaller they are spread outwardly toward the sides of the jaws so that the lower faces of the jaws have practically the same crushing capacity as the upper faces.

The jaw 18 also has a vertical movement in addition to the above lateral movement which acts to facilitate the chewing action to force the rock downwardly so that it will become wedged between the jaws before they start to crush. This is accomplished, as illustrated in Fig. 3, by placing the supporting shaft 27 a substantial distance to the rear of the crushing face of the movable jaw 18, so that, as the lower extremity of the movable jaw is swung rearwardly, its forward face will swing downwardly and as the lower extremity swings forwardly its crushing face will swing upwardly.

Renewable curved cheek plates 43 are provided to protect the side frames 11.

While a specific form of the improvement has been described and illustrated herein, it is desired to be understood that the same may be varied, within the scope of the appended claims, without departing from the spirit of the invention.

Having thus described the invention, what I claim and desire secured by Letters Patent is:—

1. Crushing apparatus comprising a stationary jaw; a movable jaw; a hinge for said movable jaw, said hinge being arranged to allow said jaw to rotate in both a vertical and horizontal plane; and means for imparting a rocking movement to said movable jaw as it approaches said stationary jaw.

2. Crushing apparatus comprising a stationary jaw; a movable jaw; a hinge for said movable jaw, said hinge being arranged to allow said jaw to rotate in both a vertical and horizontal plane; and means for imparting a rocking movement to said movable jaw as it approaches said stationary jaw, said means comprising two eccentrics, each eccentric being operatively connected by an independent toggle means adjacent one side of said movable jaw.

3. Crushing apparatus comprising a stationary jaw; a movable jaw; a hinge for said movable jaw, said hinge being arranged to allow said jaw to rotate in both a vertical and horizontal plane; and means for imparting a rocking movement to said movable jaw as it approaches said stationary jaw, said means comprising two eccentrics, each eccentric being operatively connected by an independent toggle means adjacent one side of said movable jaw, said eccentrics being secured on a common shaft.

4. Crushing apparatus comprising a frame; a stationary jaw carried in said frame; a movable jaw carried in said frame; a universal hinge for said movable jaw; and means for imparting a rocking movement to

10 said movable jaw as it approaches said stationary jaw, said means comprising two rotatable eccentrics, each eccentric being operatively connected by an independent toggle means adjacent one side of said movable jaw, each of said toggle means comprising a vertically reciprocating pitman; a toggle plate separating one side of said pitman from said frame; and a toggle bar separating the other side of said pitman from said movable jaw.

15 5. Crushing apparatus comprising a frame; a stationary jaw carried in said frame; a movable jaw carried in said frame; a universal hinge for said movable jaw; means for imparting a rocking movement to said movable jaw as it approaches said stationary jaw, said means comprising two rotatable eccentrics, each eccentric being operatively connected by independent toggle 20 means adjacent one side of said movable jaw; each of said independent toggle means comprising a vertically reciprocating pitman; a toggle plate separating one side of said pitman from said frame; and a toggle bar separating the other side of said pitman from said movable jaw, said toggle bars being arranged for universal movement at both of their extremities.

30 6. Crushing apparatus comprising a frame; a stationary jaw carried in said frame; a movable jaw carried by said supporting frame; a universal hinge for said movable jaw; means for imparting a rocking movement to said movable jaw as it approaches said stationary jaw, said hinge comprising a supporting shaft adapted to support said movable jaw and a pivot securing said movable jaw to said supporting shaft 35 so as to allow the former to swing in the plane of said shaft.

40 7. A rock crusher comprising a supporting frame; inwardly curved side frames extending above said supporting frame; a stationary jaw supported between said side frames; a movable jaw supported between said side frames, both said jaws being of greater width at their bottoms than at their tops so as to conform to the curvature of said side frames; 45 means for causing said movable jaw to approach and retreat from said stationary jaw, and an outwardly curved lip on said movable jaw adapted to extend partly under said stationary jaw.

55 8. In a crusher of the character described the combination comprising a movable jaw, means for pivoting said jaw to permit lateral oscillation thereof, a pair of eccentrics out of phase with each other, and means for connecting said eccentrics to the respective side portions of said jaw to impart lateral oscillating movement to said jaw.

60 9. A rock crusher comprising in combination a supporting frame, side frames extending above said supporting frame and curved

inwardly to provide a space which has a substantial flare outwardly at the bottom so that said space has curved sides and is substantially wider at the bottom than at the top, a stationary jaw, a movable jaw supported 70 between said flares and conforming along its side edges with the curvature of said side frames, and means for causing the movable jaw to approach and retreat from said stationary jaw.

75 In testimony whereof we affix our signatures.
